UNITED STATES PATENT OFFICE.

TONY HUBER, OF BILLANCOURT, FRANCE.

CARBURETER FOR HYDROCARBON-ENGINES.

No. 856,958.

Specification of Letters Patent.

Patented June 11, 1907.

Application filed August 8, 1904. Serial No. 220,017.

To all whom it may concern:

Be it known that I, TONY HUBER, engineer, a citizen of the French Republic, residing at Billancourt, Seine, France, have invented certain new and useful Improvements in Carbureters for Hydrocarbon-Engines, of which the following is a specification.

This invention relates to an improvement in those carbureters in which the feed is automatically effected by the suction stroke of the piston of the motor.

Most high speed internal combustion engines have hitherto been provided with automatic valves. These automatic valves present great disadvantages and especially that of being raised by the same amount under the same reduction of pressure so that the velocity of the air in the feed pipes and the carburation are in consequence always the same.

Entirely different results are obtained if positively driven valves are used so as to open according to the position of the piston and not according to the reduction of pressure caused by the piston in its suction stroke. The automatic valve has however to be abandoned if the volumes swept by the piston are very

large, for these require the employment of valves of large diameters the many disadvantages of which are well known. If however

it could be located on the feed pipe behind the valve controlled by the motor, so as to be away from any cause of deterioration it would again prove as efficient as usual. It follows therefrom that its proper position is

in the carbureter itself wherein it may serve for one or more cylinders. This very light valve without inertia will preserve all the advantages of the automatic inlet valve. When the speed of the motor varies, the quantity of

liquid fuel given out by the spraying nozzle does not remain proportional to the quantity of air introduced into the cylinder by the successive suctions and in order to preserve a mixture of constant composition it is necessary to add an additional quantity of air to

the gaseous mixture before it enters the cylinders. As the composition of the gaseous mixture corresponding to normal rate of working is modified by atmospheric conditions, the additional air inlets should be capable of being operated by hand independently of the automatic regulation due to the sucking action of the piston.

The accompanying drawings show a carbureter constructed in accordance with these principles.

In these drawings: Figure 1 is a vertical section of the carbureter, and Fig. 2 a section on line A—A of Fig. 1.

In these drawings, *a* is the air inlet of the mixture chamber, *b* is the spraying nozzle; the admission of the mixture takes place through the medium of valve *c* which is opened automatically by the suction stroke of the piston. The stem *d* of this valve carries a hollow piston *e* in the walls of which are provided ports *f* corresponding to rectangular openings *g* in the cylinder *h* in which the piston *e* moves. These ports *f* serve to regulate the additional introduction of air. A spring *i* tends constantly to bring the valve *c* on to its seat. The movements of the piston *d* uncover more or less the ports *f* but it is indispensable that these ports should never be completely closed as the permanent opening is a function of the possible minimum speed of the motor. Moreover a sleeve *j* arranged externally on the aforesaid cylinder *h* can be adjusted by hand so as to open more or less the openings *g* according to the variations of the atmospheric pressure. The additional air ports may be of variable form.

Having now particularly described and ascertained the nature of this invention and in what manner the same is to be performed I declare that what I claim is:

1. A carbureter for hydrocarbon engines comprising a casing forming a mixing chamber adapted to communicate with the engine and having a permanently-open air inlet, a spraying element arranged in said chamber in operative relation with respect to said air inlet, a valve interposed between the chamber and the engine and arranged in the path of the gases and controlled by the suction-stroke of the piston of the engine, and a piston connected with the valve and adapted to control the admission of an additional supply of air independent of the supply through said air inlet.

2. A carbureter for hydrocarbon engines comprising a casing forming a mixing chamber adapted to communicate with the engine and having a normally-open air inlet and a regulatable air inlet independent of the normally-open air inlet, a spraying device arranged in operative relation with respect to said normally-open air inlet, a valve interposed between the outlet of said chamber and the cylinder of the engine and operated by the suction-stroke of the engine, and means operated by said valve for regulating the

supply of air through said regulatable air inlet.

3. A carbureter for hydrocarbon engines comprising a casing forming a mixing chamber adapted to communicate with the engine, said mixing chamber normally open to the atmosphere, a spraying device arranged within said chamber at a point removed from the opening thereof, a valve interposed between 10 the mixing chamber and the engine, arranged in the path of the gases and adapted to be operated by the suction-stroke of the engine, and means connected with and operated by the valve for regulating an additional supply 15 of air to the gas.

4. A carbureter for hydrocarbon engines comprising a casing having an air inlet and further provided with a regulatable inlet independent of the first-mentioned inlet, a 20 spraying device arranged in said casing in operative relation with respect to the first-mentioned air inlet, a valve interposed between said casing and the engine arranged in the path of the gases and operated by the 25 suction-stroke of the engine, and a hollow piston provided with an opening, said piston connected with and operated by said valve and adapted to regulate the supply of an additional quantity of air through said regulatable air inlet.

5. A carbureter for hydrocarbon engines, comprising a casing forming a mixing chamber adapted to communicate with the engine, said mixing chamber having a permanently- 30 open air inlet and further provided with a regulatable air inlet independent of the first-mentioned air inlet, a spraying device ar-

ranged in said chamber in operative relation with respect to the first-mentioned air inlet, a valve interposed between the said chamber and the engine, arranged in the path of the gases and operated by the suction stroke of the engine, a hollow piston provided with an opening, said piston connected with and operated by said valve and adapted to regulate 40 the supply of an additional quantity of air through said regulatable air inlet, and a spring acting to constantly move said valve toward its seat.

6. A carbureter for hydrocarbon engines, comprising a casing forming a mixing chamber and provided with a normally-open air inlet and a regulatable air inlet, said regulatable air inlet positioned in said casing at an angle with respect to the normally-open air 50 inlet, a spraying device, a valve interposed between the casing and engine and operated on the suction stroke of the engine, a piston connected with and operated by the valve, and provided with an opening registering 55 with said regulatable air inlet, said piston adapted to control the admission of an additional supply of air independently of the air supply through the first-mentioned air inlet, and means for regulating the area of said 60 regulatable air inlet.

In testimony whereof I have hereunto set my hand in presence of two subscribing witnesses.

TONY HUBER.
